UNITED STATES PATENT OFFICE.

BARKER E. KIGANS, OF MARIETTA, OHIO.

HEATING-CURTAIN.

Specification of Letters Patent.

Patented Nov. 9, 1915.

1,159,952.

Application filed February 16, 1915. Serial No. 8,662.

To all whom it may concern:

Be it known that I, BARKER E. KIGANS, a citizen of the United States, residing at Marietta, in the county of Washington and 5 State of Ohio, have invented new and useful Improvements in Heating-Curtains, of which the following is a specification.

An object of the invention is to provide a heating curtain for use in connection with 10 gas or other burners, and which is so adapted to be arranged in a fire place to present a neat and effective appearance and aid in distributing or radiating heat from the flame of the burner.

15 The invention contemplates, among other features, the provision of a curtain which is preferably made of sheet asbestos and conveniently cut or formed in a size which will permit of its being accommodated in a fire-place. The curtain is preferably formed 20 in strips and, being made of asbestos, the curtain, when subjected to the heating action of the flame of a burner, will tend to radiate and impart the heat to the room in 25 which the fire-place is located, while at the same time the curtain, when heated by the flame of the burner, will present a neat and effective appearance.

In the further disclosure of the invention 30 reference is to be had to the accompanying drawings, constituting a part of this specification, in which similar characters of reference denote corresponding parts in all the views, and in which:

35 Figure 1 is a front elevation of the fire-place, showing the curtain arranged therein; and Fig. 2 is a vertical transverse sectional view taken on the line 2—2 in Fig. 1.

Referring more particularly to the views, 40 I disclose a fire-place 10 having the usual back 11 and in which is arranged a preferably horizontal tubular burner 12 connecting with a suitable gas supply 13, the flame from the burning gas issuing from the 45 burner 12 being indicated by the numeral 14. The curtain, indicated by the numeral 15, is preferably formed of a single piece of asbestos, more particularly sheet asbestos, and which, folded at its medial portion, has 50 its sides cut to provide a series of strips 16, the medial solid portion 17 of the curtain having suitable clamps 18 attached thereto and which may also encircle a horizontal

supporting bar 19 extending throughout the length of the curtain beneath its medial solid portion, with the ends of the bar projecting and secured to the back 11 of the fire-place by hangers 20, the clamps 18 being also secured to the back of the fire-place to support the curtain in a depending position as shown, with the burner arranged beneath the curtain and preferably below and between the sides thereof so that the flame of the burner, issuing up between the sides, will permit of the heat passing between the strips and thus heating a large area of the curtain so that the heat can radiate through the room. Inasmuch as the flame received between the sides of the curtain cannot readily pass between the strips, a large amount of 70 the heat produced by the flame will strike downward upon the hearth in front of the fire-place and thus radiate still another portion of the heat through the room.

With a curtain of the character described, 75 it has been found that a larger amount of heat can be produced in conjunction with a gas burner such as mentioned than with the usual gas logs or the like now generally used, the same quantity of gas being consumed in each instance. Thus it will be clear that the invention, aside from the neat and effective appearance which it will present when in use, will work a saving of fuel whether used in conjunction with a gas 85 burner or some other kind of fuel-consuming burner adapted for the purpose of heating rooms and the like.

Having thus described my invention, I 90 claim:

The combination with a fire place, of a burner located in the fire place, a horizontal bar in the fire place and supported on the back thereof, and in spaced relation to said fire place, said bar being disposed above said 95 burner, and an inverted V-shaped sheet of asbestos formed with strips and suspended from said bar in spaced relation to said burner.

In testimony whereof I affix my signature in presence of two witnesses.

BARKER E. KIGANS.

Witnesses:

J. G. NILLISON,
McCLELLAN NILLISON.
